UNITED STATES PATENT OFFICE.

HARDIN B. LITTLEPAGE, OF WASHINGTON, DISTRICT OF COLUMBIA, AS
SIGNOR OF ONE-HALF TO WILLIAM B. MATTHEWS, OF SAME PLACE.

CORD-CLAMP.

SPECIFICATION forming part of Letters Patent No. 655,155, dated July 31, 1900.

Application filed January 6, 1898. Serial No. 665,854. (No model.)

To all whom it may concern:

Be it known that I, HARDIN B. LITTLEPAGE, a citizen of the United States, residing at Washington, District of Columbia, have invented certain new and useful Improvements 5 in Cord-Clamps, of which the following is a specification.

My invention relates to a key-operated cord-clamp composed of two hinged sections, the 10 one provided with grooves and cleats therein to receive the cords and the other with transverse ribs which are adapted to adjustably interlock; and one object of my improvement is to provide a clamp which will securely 15 clutch and hold cords and ropes and prevent them from slipping when under strain.

My cord-clamp is especially adapted for use on bags which are closed or gathered at the top by ropes; but it is obviously applicable 20 to all packages which it may be desirable to secure by cords.

A further object is to provide the hasps with a plurality of teeth or catches whereby the 25 two hinged sections are made to adjustably interlock and thereby readily adapt themselves to any variations which may occur in the sizes of different ropes.

With these objects in view my invention consists in certain features of construction 30 and in combinations of parts hereinafter described, and pointed out in the claims.

In the accompanying drawings, Figure 1 is a perspective view showing the two sections thrown open, each provided with ribs or cleats, 35 and the serrated hasps carried by one of the sections. Fig. 2 is a plan view showing in dotted lines the relative positions of the ribs and cleats when the sections are closed and also the tortuous position assumed by the rope 40 or cord when pressed between them. Fig. 3 is a transverse sectional view taken along the line $x-x$, Fig. 2. Fig. 4 is a view of the locking mechanism, the top having been removed from the lock-box.

The clamp is composed of the two hinged 45 sections A and B, adapted to swing upon a hinge C, which may be of any suitable construction. The section B consists of a hollow metal casing, which may contain any desirable locking mechanism, preferably the one 50 shown in Letters Patent No. 547,082, which

were granted to me October 1, 1895. However, I do not desire to limit myself to any specific locking mechanism, for any of those in general use would be equally suitable. B 55 is also provided with a flange D, formed by the extension of the front side of the casing above the lock-box. This serves to shield the corresponding flange D' on section A, which carries the hasps E E. The section A is provided with grooves F F, adapted to receive the cords or ropes K, and provided with a plurality of staggered cleats or lugs G G, arranged in staggered relation in the grooves. These cleats are so arranged relatively to the transverse ribs H, secured to the top surface L of the lock-box B, that the ribs H lie intermediate the oppositely-arranged pairs of cleats G G when the box is closed, as best seen in Fig. 2. The outer edges or bearing-surfaces 70 of the lugs or cleats G G slope in such a manner as to cause the ropes or cords when pressed against them by the ribs H to slide over the said bearing-surfaces until they rest against the grooves in the section A and assume the 75 tortuous position as shown in Fig. 2. Ordinarily the ribs H are rigidly secured to the plate L, as shown in Fig. 1; but in cases where greater adjustability is demanded of the clamp, as when it is to be used for a variety 80 of ropes differing largely in size, I may provide the plate L with transverse depressions, in which are mounted springs N, preferably in the form set forth in Fig. 3, upon which the lugs or cleats H may be adapted to ride. 85 To prevent the displacement of the ribs, the shoulder of the hinge C will serve as a retaining means for one end. To prevent the other end from displacement, I have provided a lug or projection e, secured to the flange D and 90 projecting out over the end of the rib, thereby preventing it from entirely slipping out. The form of spring shown is thought to be best adapted for this purpose; but I do not wish to limit myself to any special kind, as any 95 other form generally known would be equally suitable for this purpose.

The section A is provided with hasps E E upon the flange D', which have their edges notched or serrated and are adapted to enter suitable openings in the surface L, when D D' will stand in juxtaposition. These

catches or teeth *a* are arranged oppositely on each side of the hasp, as best seen in Fig. 1, and since the locking mechanism is such as to be equally effective upon any pair of opposite notches it is obvious that the hasps *E* may be securely locked at any point along their edges.

In operation when the clamp has been loosely closed upon the ropes or cords they are drawn through the lock as far as desired. Then the two sections are pressed as tightly together as possible and locked securely at that point upon the hasps. As a further precaution against the rope slipping I may provide the inner surfaces of one or both sections with corrugations *O O'*, as shown in Fig. 1. These may be arranged transversely or in any other manner equally suitable to the purpose. In practice it may be desirable to use only the cleats on either section, in which case the corrugations may be dispensed with, or the corrugations may be used on either side or both, as they prove most effective.

Although I have only shown two pairs of teeth upon the hasps, I may provide them with any number desirable.

In Fig. 4 I have shown one locking mechanism which may be applied to my cord-clamp; but I show this only as a conventional type, as it is obvious that this may be changed within the scope of my invention.

Having thus described my invention, what I claim is—

1. A cord-clamp composed of two sections hinged together, one of the sections being provided with two grooves for the reception of the cords, staggered cleats in each of the grooves and a key-operated lock for holding the clamp in its closed position, substantially as described.

2. A cord-clamp composed of two sections hinged together, one of the sections being provided with two grooves for the reception of the cords, each groove having staggered cleats, the other section being provided with cleats intermediate the cleats on the first-named section, and a key-operated lock for securing the clamp in its closed position, substantially as described.

3. A cord-clamp comprising two sections, spring-actuated cleats thereon adapted to accommodate cords of different sections and a

key-operated lock for securing the clamp in its closed position, substantially as described.

4. A cord-clamp comprising two sections 55 one of which is provided with cord-grooves, each groove provided with staggered cleats, the other section provided with spring-actuated cleats and a key-operated lock for securing the sections together, substantially as described.

5. A cord-clamp comprising two sections, one section provided with a key-operated lock, the other section provided with one or more hasps, each hasp having a plurality of 65 lugs or catches with which the lock in the other is adapted to engage, whereby the clamp is adapted to accommodate cords of various sections, substantially as described.

6. A cord-clamp comprising two sections 70 hinged together, one of the sections provided with a key-operated lock and cleats, the other section grooved to receive the cords and each groove provided with staggered cleats and hasps on the latter section, each hasp provided with a plurality of lugs or catches with which the lock is adapted to engage, whereby cords of different sections may be accommodated, substantially as described.

7. A cord-clamp comprising two sections 80 hinged together, one of the sections provided with a key-operated lock and spring-actuated cleats, the other section grooved to receive the cords, and each groove provided with staggered cleats and hasps in the latter section, each hasp provided with a plurality of lugs or catches with which the lock is adapted to engage whereby cords of different sections 85 may be accommodated, substantially as described.

8. A key-operated cord-clamp composed of two sections, hinged together, the inner surface of one or both sections being corrugated, whereby the cord will be more securely prevented from slipping, substantially as described.

In testimony whereof I have hereunto set my hand in presence of two subscribing witnesses.

HARDIN B. LITTLEPAGE.
